UNITED STATES PATENT OFFICE

JOSEPH C. ANDEREGG, OF ALGOMA, WISCONSIN, ASSIGNOR TO ALGOMA NET COMPANY, INC., OF ALGOMA, WISCONSIN, A CORPORATION OF WISCONSIN

COMBINED CRIB AND SWING

Application filed May 19, 1928. Serial No. 279,057.

This invention relates to a combined crib and swing and more particularly to that type of these devices wherein the supporting part comprises a bag supported by a frame which is in turn supported by connected straps or similar flexible supporting devices.

An important object of the invention is to provide in connection with a device of this character a swingable cloth panel which may function either as a shade or escape preventer when the device is employed as a crib or as a tray when the device is employed as a swing.

A further object of the invention is to provide a device of this character which, when employed as a shade, may be supported by the supporting straps of the crib.

A still further object of the invention is to provide a device of this character which may be readily and cheaply manufactured, which will be durable and efficient in service and a general improvement in the art.

These and other objects I attain by the construction shown in the accompanying drawings, wherein for the purpose of illustration is shown a preferred embodiment of my invention and wherein:

Figure 1 is a side elevation of a combined crib and swing constructed in accordance with my invention;

Figure 2 is a plan view thereof partially broken away;

Figure 3 is a section on the line 3—3 of Figure 2;

Figure 4 is a section on the line 4—4 of Figure 1;

Figure 5 is a section on the line 5—5 of Figure 2;

Figure 6 is a detail plan view of one of the corners of the tray;

Figure 7 is a section showing the manner of connecting the cross bar of the tray with the supporting straps;

Figure 8 is a section on the line 8—8 of Figure 1.

Referring now more particularly to the drawings, the numeral 10 indicates a rectangular frame which may be conveniently formed from bar iron or steel. To this frame is secured the upper edges of the side walls

50 of a canvas or other fabric bag 11. The bot-

tom wall of this bag adjacent one end thereof is provided with suitably-bound openings 12 through which the legs of the occupant may be extended when the device is employed as a swing. The corners of the bag are cut-away, 55 as at 13, to expose the frame 10, so that supporting straps 14 may be conveniently connected thereto. The structure of these straps will be hereinafter more particularly referred to. As hereinbefore stated, the openings 12 60 are adjacent one end of the bag and beyond these openings from the adjacent end of the bag, the upper edges of the side walls are cut-away, as indicated at 15, to expose the side member of the frame.

In combination with this structure, I provide a tray, generally designated at 16, which comprises a fabric panel 17 and a U-shaped supporting frame therefor. The supporting frame includes a cross bar 18 of slightly 70 greater width than the frame 10 and having extending therefrom at points spaced inwardly from the end edges thereof parallel arms 19.

The ends of the parallel arms 19 are formed 75 as loops 20 engaging the end member of the frame which is adjacent to the openings 12 at the point where this end member is exposed by the cut-away portion 13. The ends of the cross bar outwardly of the arms 19 80 are arcuately curved or hooked as at 20^a at the same side of the U-shaped frame and in a plane which is substantially perpendicular thereto. The U-shaped frame may be conveniently fabricated from a single length of bar-iron or steel, the center of which forms a cross bar and the ends of which are reverted inwardly to form the projecting portions 20^a and then bent out to form the arms 19. The fabric panel 17 has an end edge 85 thereof hemmed about the cross bar 18 between the arms, as indicated at 21, and has at its side edges openings 22 which are preferably button-holed to reinforce the same and through which the arms 19 may pass to thread 90 the edges of the panel thereto. This mounting of the fabric panel upon the frame permits the edge of the panel remote from the cross bar to be moved toward the cross bar 95 so that a space may be provided between the 100

inner edge of the tray and the end of the bag frame to which the tray is pivoted.

It will be obvious that by swinging the tray about the end member as a pivot, this tray may be arranged either above or below the bag. When disposed above the bag, the hooks of the tray may be disposed either above or below the side members of the frame 10 by simply engaging these side members which are flexible and spreading them to permit the passage of the ends of the cross bar therebetween. When the tray is disposed above the bag with the hooks beneath the side members of the frame 10, the tray may not be elevated by reason of the fact that these hooks will engage the side members of the frame 10 and prevent such elevation and may not move downwardly except for a short distance due to the fact that the hooks will engage the bag at the edges of the openings 15 and limit such downward movement. When the tray is beneath the bag, the bag will, of course, be held up by the tray at one end and at this time, the side members must be spread and the hooks passed between the side members so that they lie above the side members and serve as a support for the bag. When the tray is arranged above the bag and beneath the side members of the frame 10, it will be quite obvious that a child lying in the crib will not escape therefrom, for the simple reason that any effort of the child to rise will be frustrated by the engagement of the hooks with the frame. At this time, if desired, the fabric covering of the tray may either be left extended to its full length or the free edge thereof shifted toward the cross bar 21, thereby exposing the face of the child.

40 The supporting straps 14 hereinbefore referred to are preferably two in number, each strap having its ends engaged with the frame at corresponding ends thereof. The bight of the strap is passed through an eye 23 and then connected with a buckle element 24.

50 This buckle element is adjustable upon the straps so that the effective length of each strap may be adjusted. The eyes through which the straps pass are preferably, in the case of one strap, a ring and, of the other strap, the eye of the shank of a snap hook 25. Each strap has secured thereto in properly spaced relation to the ends thereof loops 26 adapted to receive the hooks 20^a of the tray. 55 In the use of a device of this character as a swing, the tray element is usually disposed above the bag and swung so that the hooks 20^a rest upon the frame. When engaged with the frame, this tray element performs its normal function. In event the position of the swing is such that the child is facing a glaring light, this may be cut off by swinging the tray upwardly and engaging the ends of the hooks in the loops 26 of the straps. 60 If desired, the tray may be arranged below

the bag when the device is employed as a swing. In this case, one end of the bag is held suspended by the tray. When this arrangement is employed, the fabric cover of the tray can be shifted toward the cross bar 70 and assists in forming a pad upon the cross bar to cushion the same. When employed as a swing, the adjacent ends of the straps may be connected to one another and connection made with a common support therefor or independent supports may be employed. This is likewise the case when the device is used as a crib.

When employed as a crib, the tray is swung to the opposite side of the frame and the frame members, after the child has been placed in the crib, are sprung apart so that the cross bar may be placed therebelow and the hooks engaged with the side members from beneath. When engaged, the tray may not be forced upwardly by pressure applied from beneath so that it acts as an escape 85 pre-venter. It further serves both as a sun shade and as a means for excluding insects.

It will be obvious from the foregoing that a tray of this character forms an extremely convenient attachment for the crib and may be very readily and rapidly adjusted to its various uses.

It will also be obvious that the construction hereinbefore set forth is capable of a certain range of change and modification without materially departing from the spirit of the invention and I accordingly do not limit myself to such specific structure except as hereinafter claimed.

I claim:—

1. In combination with a combined crib and swing comprising a rectangular frame and a bag secured at its edges to the frame and provided in its bottom adjacent one end with openings for the passage of the legs of an occupant, a tray pivoted to the adjacent end of the frame and including a cross bar adapted to engage the sides of the frame, supports for the frame, and means upon said supports for engaging the ends of the cross bar to hold the tray in a position where it extends upwardly from the frame and forms a sun shade.

2. A structure as set forth in claim 1, wherein the ends of the cross bar of the tray are bent to form hooks to engage over the frame and the bag is cut away at the point of engagement of the cross bar with the sides of the frame and the side members of the frame are flexible to permit their separation to a point permitting the free end of the tray to pass therethrough whereby said hooks may be engaged with the frame from above or beneath.

3. A device as set forth in claim 1, wherein the supports for the frame comprise flexible elements having loops attached thereto

for the reception of the ends of the cross bar.

4. In combination with a combined crib and swing comprising a rectangular frame and a bag secured at its edges to the frame and provided in its bottom adjacent one end with openings for the passage of the legs of an occupant, a tray pivoted to the adjacent end of the frame and including a cross bar adapted to engage adjacent its ends the sides 10 of the frame, said tray being swingable about said end of the frame bar to either the in or out side of the bag, the bag being cut-away at the point of engagement of the ends of the cross bar with the frame, the frame being 15 resilient to permit springing of the sides to thereby enable the cross bar to be arranged either above or below the frame.

5. A device as set forth in claim 4, wherein supporting straps are provided for the 20 frame and engage the frame at the end corners thereof, the supports at the end of the frame to which the tray is pivoted having loops in which the ends of the cross bar may be engaged.

25 6. A device as claimed in claim 4, wherein the ends of the cross bar are bent to form hooks for engagement with the sides of the frame.

7. A device as claimed in claim 4, wherein 30 supporting straps are provided for each end of the frame, the ends of the straps being secured to the corners of the frame, the straps at the end of the frame to which the tray is pivoted having means for engaging the cross 35 bar of the tray to hold the tray in alignment with the straps.

8. A device as claimed in claim 4, wherein 40 supporting straps are provided for each end of the frame, the ends of the straps being secured to the corners of the frame, the straps at the end of the frame to which the tray is pivoted having means for engaging the cross 45 bar of the tray to hold the tray in alignment with the straps, the straps at opposite ends of the frame having means whereby they may be detachably connected to one another,

9. In a structure of the character described and in combination, a rectangular frame, a 50 bag secured at its edges to the frame and provided in its bottom with openings for the passage of the legs of an occupant, a tray pivoted to an end member of the frame in a manner to permit its being swung thereinto and having at its sides members to engage the side members of the frame, the side members of the frame being flexible to permit their separation to an extent permitting passage of the free end of the tray therethrough.

60 10. A device as claimed in claim 9 wherein said tray comprises a U-shaped frame the ends of the arms of which are pivoted to the end member of the first named frame and a fabric covering for said tray frame secured 65 to the cross bar of the frame and having slid-

ing engagement with the arms of said tray frame.

In testimony whereof I hereunto affix my signature.
